US00D875361S

(12) **United States Design Patent** (10) **Patent No.:** **US D875,361 S**
(45) **Date of Patent:** **** Feb. 18, 2020**

(54) **SHOE**(71) Applicant: **PUMA SE**, Herzogenaurach (DE)(72) Inventors: **Romain Girard**, Lauf an der Pegnitz (DE); **Matthias Hartmann**, Forchheim (DE)(73) Assignee: **Puma SE**, Herzogenaurach (DE)(***) Term: **15 Years**(21) Appl. No.: **29/700,619**(22) Filed: **Aug. 3, 2019****Related U.S. Application Data**

(60) Continuation of application No. 29/682,372, filed on Mar. 5, 2019, which is a division of application No. 29/621,562, filed on Oct. 10, 2017, now Pat. No. Des. 855,953.

(57)

CLAIM

The ornamental design for a shoe, as shown and described.

DESCRIPTION

FIG. 1 is a left side perspective view of an ornamental design for a shoe; and,

FIG. 2 is a left side view of the shoe of FIG. 1. The dash-dash-dash lines are included for the purpose of illustrating portions of the shoe that form no part of the claimed design. The contrast in shading represents a contrast in appearance only.
